ABSTRACT

It is a propeller with an injection apparatus, that extends outwardly from a vertical water pole, rotates such that it forms a peripheral movement through its water pressure in dishwashers. It is a rotating propeller with a 2K sealing element and a clamp structure and an injection feature, that is defined with a vertical leaning surface at its end portion and with an inner edge shape such that it has a partial cylindrical shape, wherein it is molded with a PP material, wherein body of each thereof is of longitudinal and wherein it comprises a lower wall and an upper wall.

ROTATING INJECTION PROPELLER WITH 2K-SEAL

The present invention relates to, in general, a rotating injection apparatus and a molded plastic injection arm with a 2K-seal system, formed in an integrated manner therewith. The inventive rotating injection propeller comprises a 2K-seal element that is formed of PP material, is resistant to higher temperatures, chemicals, and pressure and has a stainless and light body, wherein it relates to ensuring sealing by stretching and compressing the sealing elements with a triangle and round section thereon by means of 2K (dual component) technology without requiring any sealing test. Interior stress may occur due to the hot welding process (Hot Plate) or visible defects, sealing problems, residual stress and distortions and areas affected by the heat may occur on the welding area due to the vibration welding process. In such cases, sealing problems may occur due to the fact that the desired level of adhesion cannot be ensured.

RELATED TECHNICAL FIELD OF THE INVENTION

It is a propeller with an injection apparatus, that extends outwardly from a vertical water pole, rotates such that it forms a peripheral movement through its water pressure in dishwashers and in machines with similar washing function. It is a rotating propeller with an injection feature, that is defined with a vertical leaning surface at its end portion and with an inner edge shape such that it has a partial cylindrical shape, wherein it is molded with a PP material, wherein body of each thereof is of longitudinal and wherein it comprises a lower wall and an upper wall. In machines with such features, dirty dishes or other products are placed into a washing chamber and they are subjected to a high-flow water injection effect of washing sprayers. Washing water is circulated for a sufficient period so as to loosen and remove food residues on the products and the injection processes are maintained and said residues are removed by means of the powerful water injection and washing fluid. Since the propeller with said injection feature loses its sealing property causes to decrease the water injection intensity on the propeller, the washing performance is affected negatively.

STATE OF THE ART AND PROBLEMS AIMED TO BE SOLVED THROUGH THE INVENTION

In the prior art, the sensitivity of the plastics against bolting may initiate cracks because of rivet or bolting, deformations on the plastics may occur due to bolting and therefore, adhesion through hot welding process or vibration welding process in the assembly comes into the forefront. It is necessary that plastic materials firstly are softened and then hardened again in the welding process. Two areas of thermoplastics to be welded through the hot welding process should be melted and sufficient pressure should be implemented for the adhesion. Through this method, internal stresses occur during melting and cooling the partial area on the plastic. Another assembly process is a welding process carried out by means of applying vibration and pressure on plastics in the vibration welding mold. Materials should be heated up around the melting temperature for this process and are assembled through the vertical vibration method. Visible defects, residual stress and distortions, and areas affected by the heat may occur in the welding area due to the vibration welding process. When water injection apparatuses of the dishwasher are manufactured through Hot Plate

(How Welding) method or vibration welding, the desired sealing effect cannot be ensured, in case the welding quality is insufficient, thereby affecting the performance of the machine negatively. So as to avoid such cases, every part is subjected to a sealing test after the welding and defective parts are sorted out. This also causes additional cost and time loss.

BRIEF DESCRIPTION OF THE INVENTION

10 It is a propeller with an injection apparatus, that extends outwardly from a vertical water pole, rotates such that it forms a peripheral movement through its water pressure in dishwashers.

15 It is a rotating propeller with an injection feature and a 2K sealing element, that is defined with a vertical leaning surface at its end portion and with an inner edge shape such that it has a partial cylindrical shape, wherein it is molded with a PP material, wherein body of each thereof is of

20 longitudinal and wherein it comprises a lower wall and an upper wall. It relates to ensuring the sealing effect by means of stretching and compressing the sealing element with a triangle and round section thereon with 2K (dual component) technology, that can be de-mounted by means of its clamp structure. By means of the sealing element surrounding the entire assembled surface of the lower part and the groove surrounding the entire surface on the upper part corresponding to the assembly, since the sealing element is seated in the groove after the assembly, the absolute sealing effect is ensured without performing any test, thereby providing the sealing guaranty. Groove and sealing elements on the lower and upper propellers may be repositioned such that they are on the lower and upper parts.

DETAILED DESCRIPTION OF THE INVENTION

35 The present invention relates to a rotating injection propeller with a 2K sealing element, that comprises an injection apparatus extending outwardly from a vertical water pole in 40 dishwasher, comprising a peripheral flange and a cylindrical body, and that can be opened and closed by means of its clamp structure. Dirt accumulated on the injection apparatus over time choke up the injection mouth and affect the 45 injection performance negatively. Body with a 2K sealing element and a clamp structure allows for cleaning injection mouths by means of its attachable and detachable structure. It is a rotating propeller with an injection feature and a 2K sealing element, that is defined with a vertical leaning surface at its end portion and with an inner edge shape such 50 that it has a partial cylindrical shape, wherein it is molded with a PP material, wherein body of each thereof is of longitudinal and wherein it comprises a lower wall and an upper wall.

55 Upper and lower elements are attached to each other by means of clamps and there is a groove molded on one of the adjacent surfaces of the related elements and a sealing element on the other surface, that is manufactured with 2K manufacturing technology. The sealing element surrounding 60 the entire assembled surface of the lower part is seated precisely in the groove surrounding the entire surface on the upper part corresponding to the assembly, thereby ensuring the sealing effect. By means of said manufacturing technique, the rotating injection propeller with a 2K sealing 65 feature is manufactured without requiring any sealing test, additional cost and time loss, causing any internal stress on the plastic part. Groove and sealing elements on the lower

and upper propellers may be repositioned such that they are on the lower and upper parts.

The upper part (1) of the inventive propeller constitutes the upper half portion of the propeller and the injection washing ends are on said portion. Sealing groove (4) or sealing element (3) may be on said part. It completes the propeller when it is assembled with the lower part (2).

The lower part (2) of the inventive propeller constitutes the lower half portion of the propeller and ends that rotate the propeller are on said portion. Sealing groove (4) or sealing element (3) may be on said part. It completes the propeller when it is assembled with the upper part (1).

The sealing element (3) of the inventive propeller is on the upper part (1) or lower part (2). Its task is to ensure the sealing effect by being seated in the groove (4) on the other propeller part.

The sealing groove (4) of the inventive propeller is on the upper part (1) and lower part (2). Its task is to ensure the sealing effect by seating the sealing element (3) on the other propeller part therein.

Mounting clamps (5) of the inventive propeller clamp the upper propeller part (1) and lower propeller part (2) to each other and both ensure the sealing effect and keep the propeller in one piece by means of combining the sealing groove (4) with the sealing element (3).

DESCRIPTION OF THE FIGURES

REFERENCE LIST

1—Propeller Upper Part

2—Propeller Lower Part

3—Upper Part Sealing Element

4—Lower Part Sealing Groove

5—Propeller Mounting Clamps

What is claimed is:

1. Rotating injection propeller assembly with a sealing effect, comprising a first propeller comprising:

an upper part (1);

a lower part (2) positioned opposite the upper part (1) and engaged to the upper part (1); and

a first sealing element (3) provided between the upper part and the lower part (2);

wherein,

the first sealing element (3) defines a triangle section on a first side of the first sealing element (3), the triangle section providing sealing effect by stretching against the upper part; and

the first sealing element (3) defines a round section on a second side of the first sealing element (3), the second side being opposite the first side, the round section providing the sealing effect by compressing against the lower part.
